(57) **CLAIM**

The ornamental design for the handle texturing, as shown and described.

DESCRIPTION

FIG. 1 is a left side perspective view of my new handle texturing;

FIG. 2 is a right side perspective view thereof;

FIG. 3 is left side perspective view of a second embodiment of my new handle texturing; and,

FIG. 4 is a right side perspective view of the second embodiment of my new handle texturing.

The broken lines in FIGS. 1 through 4 are environmental only and form no part of the claimed design.

1 Claim, 2 Drawing Sheets

FIG. 1

FIG. 2

FIG. 3**FIG. 4**
